FISHING LURE

John Eslinger, Chicago, Ill.

Application March 12, 1958, Serial No. 50,002

Term of patent 14 years

(Cl. D31—4)

Fig. 2 is a right side elevational view thereof;

Fig. 3 is a front elevational view thereof; and

Fig. 4 is a vertical cross-sectional view taken substantially along the line 4—4 in Fig. 2.

I claim:

The ornamental design for a fishing lure, as shown.
